[57] CLAIM

The ornamental design for a drawing implement storage device, substantially as shown and described.

DESCRIPTION

FIG. 1 is a perspective view of a drawing implement storage device embodying my new design;

FIG. 2 is a front elevational view thereof;

FIG. 3 is a top plan view thereof; and

FIG. 4 is a fragmentary sectional view thereof, to an enlarged scale, taken along line 4—4 of FIG. 1.

Fig. 1.

Fig. 4.

Fig. 2.

Fig. 3.
